UNITED STATES PATENT OFFICE.

ROY L. THOMPSON, OF BEND, OREGON.

DOOR-CATCH.

1,391,920.

Specification of Letters Patent. Patented Sept. 27, 1921.

Application filed September 23, 1920. Serial No. 412,161.

To all whom it may concern:

Be it known that ROY L. THOMPSON, a citizen of the United States, residing at Bend, in the county of Deschutes and State 5 of Oregon, has invented certain new and useful Improvements in Door-Catches, of which the following is a specification.

This invention relates to improvements in spring catches, having for an object to 10 provide a catch particularly adaptable for use in connection with the doors of cabinets, cupboards or any analogous or similar types of doors whose construction is generally light, whereby such a door will be 15 securely retained in a closed or locked position when engaged by the catch, and which, when said catch is disengaged therefrom, will have an outward or opening thrust imparted thereto, thus materially facilitating 20 the swinging of the same to its full open position if so desired.

Among other aims and objects of the invention may be recited a catch of the character mentioned with a view to compactness 25 and in which the number of parts is few, the construction simple, the cost of production small, and furthermore, a catch which will effectually function for the purpose to which it is designed.

30 Other objects will be in part obvious and in part pointed out, hereinafter.

In order that the invention and its mode of operation may be readily understood by persons skilled in the art, I have in the accompanying 35 illustrative drawings and in the following detailed description based thereon, set out a particular embodiment of the same.

In these drawings:

40 Figure 1 is an inside view in elevation of a horizontally swinging door and its casing with the catch applied thereto, and

Fig. 2 is an edge view in elevation of the casing showing the catch in side elevation also.

Having more particular reference to the drawings, in connection with which like characters of reference will designate corresponding parts throughout the several 50 views, 1 indicates a door casing, such for instance, as is to be found in any ordinary cabinet or cupboard, receiving therein a hinged horizontally swinging door 2.

The improved catch comprises a spring 55 plate 3, the upper portion of which is off-

set as at 4 and provided with an opening for receiving the screw threaded extension 5 carried on the inner end of the push rod 6, this push rod being provided with a suitable head or thumb piece 7 and being located adjacent the outer side of the casing 1 for an obvious purpose. A nut 5' may be, and preferably is, turned into engagement with the screw threaded end 5 and has engagement with the offset 4 of the catch plate 60 for coupling the same to the push rod 6. Furthermore, if desired, a suitable form of bushing 8 may be arranged in the opening through which the push rod 6 passes, and obviously, will afford an effectual bearing 65 for said rod. An inwardly disposed cupped extension 9 is formed on the lower end of the inwardly inclined spring catch plate 3 and receives one end of the coil spring 10 therein, the remaining end of the spring 70 being seated in the recess 11 formed in the casing 1. To provide a mounting for the plate 3, the same is formed with a substantial right angularly disposed finger 12 having pivotal connection at 13 with an anchor 75 plate 14 secured to the edge of the casing 1 by screws 15, the said finger having a hooked element or catch 16 formed thereon and adapted to be engaged, at times, with a laterally extending pin 17 carried on the 80 adjacent edge of the horizontally swinging door 2, the outer marginal portion of the catch 16 being provided with a rounded bearing surface in order that the pin 17 may 85 be engaged therewith by merely forcing the door inwardly to its closed position.

By reason of the connection of the coil spring 10 with the cupped extension 9 on the lower end of the inwardly inclined catch plate 3, it will be understood that the 90 lower end of this catch plate will be normally maintained in spaced relation to the casing 1 and its door 2, and in consequence by reason of the pivotal connection of the finger 12 with the casing 1, the catch 16 95 will be normally maintained in position for engaging and retaining the pin 17 on the door 2. However, by imparting an inward thrust to the push rod 6, the catch plate 3 will be rocked against its inherent tension 100 and the tension of the coil spring 10 thereby swinging the catch 16 upwardly and disengaging the same from the pin 17 in order 105 that free outward movement of the door 2 will be permitted. When pressure is re- 110

moved from the push rod 6, however, the same will immediately return to its normal or outermost position under influence of the spring 10.

5 A lateral ear 18 is formed on that side of the catch plate 3 adjacent the door 2 and has riveted or otherwise connected thereto an arcuate spring arm 19, the free end of which is reversely curved as at 20 to prevent mar-
 10 ring or scratching of the door 2 when en-
 gaged therewith. In this connection, it should be noted that the curve of the arcuate spring arm 19 substantially corresponds to the combined thickness of the
 15 casing 1 and the distance between the inner side of the casing and the catch plate 3, when the latter is in its normal position. Hence, when the door 2 is swung to full closed position, the arcuate spring 19 will
 20 be flexed upon itself, and thus placed under a tension which will be sufficient, with dis-
 engagement of the catch 16 from the pin 17 on said door, to impart an outward or open-
 25 ing thrust to the door immediately upon the inward pushing of the push rod 6. The connection of the arcuate spring 19 with the ear 18 is, to a certain extent, pivotal in order that the spring may be adjusted to whatever position it is desired to be engaged
 30 with the inner side of the door 2, such for instance, as is shown by the dotted lines in Fig. 1.

From the foregoing it will be understood that with my improved form of catch, all difficulty heretofore experienced in the opening of cabinet, cupboard and similar types of light doors, will be eliminated, inasmuch as with depression of the push rod 6 the catch 16 will be swung upwardly out of engagement with the door pin or keeper 17, and immediately thereafter, an outward thrust will be imparted to such door by reason of the tension under which the arcuate spring 19 has been placed with the closing of such door. Also, with the removal of pressure from the push rod 6, the catch plate 3 with the catch 16 will be returned to their normal positions ready for reengagement with the door pin 17. It is to be furthermore appreciated, that with the rocking of the catch plate 3 under influence of the push rod 6, the tension of the arcuate spring 19 engaging the inner side of the door 2, is materially increased, which naturally tends to impart a greater or outer opening to such door with disengagement of the catch 16 from the door pin 17.

Manifestly, the construction shown is capable of considerable modification, and such modification as is within the scope of my claims, I consider within the spirit of my invention.

I claim:

1. A device of the character described, comprising a catch-carrying plate pivoted

to the inner face of one side of a door casing and adapted for engagement with the adjacent edge of the door, means for rocking said plate to disengage the catch from the door, and spring means secured to and movable with the plate operable upon disengagement of the catch from said door to impart an opening thrust to the latter. 70

2. A device of the character described comprising a catch-carrying plate pivoted 75 to the inner face of one side of a door casing and adapted for engagement with the adjacent corresponding side of the door, means for facilitating rocking of said plate to disengage catch from the door, and an outwardly extending arcuate spring connected to one portion of said plate engaging the door under tension when in its closed position and being operable upon disengagement of the catch from said door to 80 impart an opening thrust to the latter. 85

3. A device of the character described, comprising a catch-carrying plate pivoted to the inner face of one side of the door casing adapted for engagement with the corresponding edge of the door, manually operable means for facilitating rocking of said plate to disengage the catch from the door, and an outwardly extending arcuate spring adjustably connected to one portion of said plate engageable by said door and placed under tension upon closing of the latter, and operable upon disengagement of the catch from the door to impart an opening thrust to such door. 90 95

4. A device of the character described, comprising an inwardly inclined catch-
 carrying plate engageable with the door, the lower end of which is normally closed from the inner face of that side of the 105 door casing to which the same is pivoted, manually operable means engaging the upper end of said plate for facilitating rock-
 ing of the same to disengage the catch from the door, and an outwardly extending ar-
 110 cuate spring adjustably connected to one portion of the plate engageable with said door and placed under tension thereby upon movement of the same to its closed position, said spring being operable immediately 115 upon disengagement of the catch from the door to impart an opening thrust to the lat-
 ter.

5. A device of the character described, comprising a spring plate having the upper portion thereof offset, while the body portion thereof is arranged at an inwardly inclined angle to that face of a door facing to which the same is attached, a right angular extension on one side of the plate 120 125 pivoted to a portion of the edge of the casing and having a curved catch formed in its outer end engageable with the door, a push rod passing through the casing and connected to the offset portion of the plate, 130

spring means engaging the lower end of said plate for normally maintaining the same in spaced relation to the adjacent portion of said casing, and an outwardly extending arcuate spring adjustably connected to one side of the lower portion of said plate engageable by said door and placed under tension by the same upon closure thereof, said arcuate spring being operable immediately upon this disengagement of 10 the catch with the door for imparting an opening thrust to the latter.

In testimony whereof I affix my signature.

ROY L. THOMPSON.
